(57) **CLAIM**

The ornamental design for a two-port compensator, as shown and described.

DESCRIPTION

FIG. 1 is an isometric view of a first embodiment of a two-port compensator;

FIG. 2 is another isometric view of the two-port compensator shown in FIG. 1;

FIG. 3 is a front view of the two-port compensator shown in FIG. 1;

FIG. 4 is a left side view of the two-port compensator shown in FIG. 1;

FIG. 5 is a rear view of the two-port compensator shown in FIG. 1;

FIG. 6 is a right side view of the two-port compensator shown in FIG. 1;

FIG. 7 is a top view of the two-port compensator shown in FIG. 1;

FIG. 8 is a bottom view of the two-port compensator shown in FIG. 1;

FIG. 9 is an isometric view of a second embodiment of a two-port compensator;

FIG. 10 is another isometric view of the two-port compensator shown in FIG. 9;

FIG. 11 is a front view of the two-port compensator shown in FIG. 9;

FIG. 12 is a left side view of the two-port compensator shown in FIG. 9;

FIG. 13 is a rear view of the two-port compensator shown in FIG. 9;

FIG. 14 is a right side view of the two-port compensator shown in FIG. 9;

FIG. 15 is a top view of the two-port compensator shown in FIG. 9; and,

FIG. 16 is a bottom view of the two-port compensator shown in FIG. 9.

(Continued)

The portions of the two-port compensator shown in broken lines form no part of the claimed design.
